CLAIM

The ornamental design for a display panel with a computer-generated icon as shown and described.

DESCRIPTION

FIG. 1 is a plan view showing a first image in a transitional sequence of a display panel with a computer-generated icon showing our new design;

Fig. 2 is a second transitioning image thereof;

Fig. 3 is a third transitioning image thereof; and,

Fig. 4 is a fourth transitioning image thereof.

The appearance of the transitional image sequentially transitions between the images shown in FIGS. 1-4. The process or period in which one image transitions to another image forms no part of the claimed design.

The even-dash broken lines illustrate portions of the icon and form no part of the claimed design. Dot-dash broken lines show a portion of the display panel, are boundaries of the claimed design and form no part of the claimed design.
